[57] CLAIM

The ornamental design for a personal computer assembly, as shown and described.

DESCRIPTION

FIG. 1 is a slightly enlarged top front and right side perspective view of a personal computer assembly showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front elevational view thereof wherein two speakers are shown attached to the sides; and,

FIG. 9 is a front elevational view thereof wherein a handset is shown attached to the side.

In FIGS. 8 and 9 the two speakers and handset are shown in broken lines for illustrative purposes only and form no part of the claimed design.
